BATHING CAP

J. Claudine Johnson, Rockford, Ill.

Application September 3, 1938, Serial No. 228,291

5 Claims. (Cl. 2-68)

My invention relates to a new and improved bathing cap.

I am aware of the numerous attempts made to produce a bathing cap that will exclude the water so as to keep the bather's hair dry. It is well known that the bathing caps now available on the market are not actually water-tight and give only a small degree of protection. Apparently the majority of the sealing means provided heretofore were designed on the theory that the entrapped air in the cap could be relied upon to keep out the water. However, I have found that even the best bathing caps designed with that in view are by no means water-tight. It is, therefore, the principal object of my invention to provide a bathing cap having sealing means therein designed to operate on a different principle, namely, that the pressure of the water tending to enter acts to increase the pressure against the head of the water excluding flange, so that the greater the water pressure becomes the greater the sealing effect.

Another object of my invention is to provide a sealing flange in a bathing cap having a reinforcing and stiffening bead on the edge thereof, so as to add durability and assure a better sealing action, by eliminating the danger of fraying at the edge, and also aid the wearer in getting the flange in the proper position when the cap is applied, the bead affording a place for the wearer to grasp the flange by the finger-tip and guide it to a position projecting downwardly all of the way around the head.

Still another object is to provide a bathing cap with sealing means, the addition of which means very little if any added cost over the cost of bathing caps now available.

The invention is illustrated in the accompanying drawing, in which—

40 Figure 1 is a perspective view showing a bathing cap equipped with the novel sealing means provided in accordance with my invention, the cap being shown as it appears in use;

45 Fig. 2 is a sectional detail on the line 2—2 of Fig. 1 on a larger scale;

Fig. 3 is a sectional detail similar to Fig. 2, but showing the sealing flange as it appears in relation to the edge of the cap in undistorted condition;

50 Fig. 4 is a section similar to Fig. 3, showing a modified or alternative construction;

Fig. 5 is a sectional detail similar to Fig. 2, showing a different sealing flange which, however, operates on the same principle, generally speaking, and

Figs. 6 and 7 are views related to Fig. 5 similarly as Figs. 3 and 4 are related to Fig. 2.

Similar reference numerals are applied to corresponding parts throughout the views.

Referring to Figs. 1 to 3, reference numeral 8 designates the body of the cap which may be made in any usual or preferred manner, the kind now most commonly used being molded from elastic material, such material being desirable because it may be distended to fit the contour of the wearer's head. At 9 is indicated one of the usual ear flaps by means of which the cap is fastened securely in place on the head with a chin strap 10 equipped with a snap fastener 11 at one end. The cap's noticeable but not objectionable annular welt 12 which extends completely around the head, over the ears, results from the added thickness due to the T-shaped sealing flange or strip 13, provided in accordance with my invention, reaching completely around the inner circumference of the cap in upwardly spaced relation to the edge portion 14 that defines the head opening. Now, the flange 13 will preferably be molded integral with the body of the cap, although, of course, I may, as shown in Fig. 4, provide a separate strip 15 adapted to be cemented to the inside of the body 8a and having thereon a T-shaped flange 13a for cooperation with the edge 14a of the cap. The integral construction is at present considered preferable. In either event the web 16 constituting the leg of the T spaces the cross-portion 17 of the T from the edge portion 14 so as to define an annular water trapping channel 18 between the sealing flange 13 or 13a and the edge portion 14 or 14a of the cap. While the flange 13 or 13a is in engagement with the head of the wearer, water entering the channel 18 between the edge portion 14 of the cap and the flange exerts pressure tending to cause the flange to seat more tightly against the head, whereby better to exclude water. In other words, the greater the water pressure becomes, the greater the sealing effect produced. An enlarged annular bead 19 defines the lower edge of the flange 13 or 13a and serves to reinforce the sealing flange so that there will be no danger of the lower edge becoming frayed and consequently giving an unsatisfactory sealing effect. The bead has a tendency to impress itself slightly into the skin, just enough to give better assurance of good sealing effect without, on the other hand, giving discomfort to the wearer. This bead 19 is also an aid to the wearer in applying the cap properly, because the finger tips can be run along this bead to make certain that the

flange is projecting downwardly and is properly engaged with the head at all points. The broad expanse of surface afforded by the flange 17 which bears against the head, as shown in Fig. 5, avoids any likelihood of the bead 19 impressing itself to an uncomfortable extent into the skin.

In operation, the sole reliance for keeping the hair dry is placed upon the sealing flange 18 or 18a, as the case may be, which in cooperation with the associated edge portion 14 or 14a of the cap provides a continuous channel 18 all the way around the head to intercept the water. The pressure exerted by the trapped water presses the flange 18 or 18a more and more tightly against the head the greater the pressure becomes, and in that way a very effective seal is produced. While the principal seal is along the beaded edge 19 of the flange, it is obvious that the wide engagement with the head of the rest 10 of the cross-portion 17 of the T-shaped flange 18 affords an extremely reliable seal also, and there is therefore little danger of any water finding its way through. In many other bathing caps there is too much reliance placed upon that 15 portion corresponding to the edge portion 14 in the present cap fitting tightly enough to act as a seal. I have found that water finds its way easily under this edge portion, and, in fact, I contemplate having this edge portion in the 20 present cap fit reasonably loosely, as indicated by the space left between the head and the edge portion 14 in Fig. 2. It is obvious that even though this edge portion may contact the head at some points, there will be no interference with 25 the sealing function, inasmuch as the channel 18 extends all the way around the head and, being filled with water, the pressure developed therein at one point is substantially equalized all the way around, making for a uniformly good seal 30 at all points. So far as the T-shaped flange 18 or 18a is concerned, it will of course be stretched in the application of the cap to the head, so that the beaded edge 19 and the sealing band formed by the adjacent flange portion 17 will have snug 35 water-tight engagement with the head.

The sealing flange 23 shown in Figs. 5 and 6 has a generally similar result and is molded integral with the cap body 8' or provided on a separate strip 25, as shown at 23a in Fig. 7, adapted 40 to be cemented in place on a body 8b. The flange 23 or 23a normally projects downwardly and inwardly relative to the edge portion 14 or 14a of the cap, whereby to provide the annular channel 18a for sealing purposes, similarly as the 45 channel 18 is provided in the other constructions, above described. The bead 29 in this case functions similarly as the bead 19 in the other form, namely, it avoids danger of the sealing edge becoming frayed and ineffectual as a sealing means, 50 while at the same time affording a good, continuous ring contact between the flange and the head of the wearer to exclude water. Here again, the bead facilitates the operator getting the flange into the proper position, projecting downwardly as shown in Fig. 5, so as to form the water trapping channel 18a throughout the inner circumference of the cap. The flanges 23 and 55 23a, of course, tend to assume the positions of downward and inward inclination by themselves, 60 but it is obvious that in the application of the cap to the head there is danger of the flange being deflected upwardly to a position where it would not cooperate with the edge of the cap to provide the important water trapping channel 65 18a, and for that reason it is desirable to have 70 75

the bead 29 which permits one to get hold of the flange easily with the finger-tips and guide it to the desired position.

It should be clear that I have provided a bathing cap of simple and economical construction. 5 The provision of the improved sealing means herein disclosed does not add materially to the cost of the cap. The present improved cap can be produced at about the same cost as the old unimproved type. 10

It is believed the foregoing description conveys a good understanding of the objects and advantages of my invention. The appended claims are drawn with a view to covering all legitimate modifications and adaptations. 15

I claim:

1. A bathing cap comprising a hollow body of flexible material having a head opening at the bottom defined by a marginal edge portion adapted to fit loosely around the head of the wearer, 20 and a sealing flange of elastic material extending entirely around the interior of said body and joined along its outer edge portion with said body in upwardly spaced relation to the edge of the marginal edge portion, said flange having a 25 free inner edge portion which when the cap is applied to the head extends downwardly from the line of connection between the flange and body in laterally spaced relation to the aforesaid marginal edge portion of the body of the 30 cap so as to form with said marginal edge portion a continuous water catching channel entirely around the interior of the body of the cap, the inner edge portion of the flange being enlarged to define a continuous circumferential bead 35 on the edge thereof, which projects inwardly and outwardly relative to the flange, the inwardly projecting portion of the bead forming a sealing means for impressing engagement with the head, the outwardly projecting portion of the bead 40 facilitating correct placement of the beaded edge of the flange on the head, said bead also reinforcing said edge portion, said beaded edge portion being adapted to be stretched in the application of the cap to the wearer's head so that 45 the beaded edge is caused to lie in snug water-tight engagement with the head and seal off the rest of the interior of the body of said cap from said channel.

2. A water-tight bathing cap comprising a body 50 of elastic material having a free lower edge defining the head-admitting opening, and above said edge within the body a single continuous circumferentially extending water catching flange attached at its one edge to the body and having 55 a free edge portion, the free edge portion of the flange being formed with relation to that portion joined to the body of the cap so as to define a generally T-shaped cross-section, the cross-portion of the T being disposed substantially parallel to the adjacent wall of the cap and forming an annular sealing band extending entirely around the interior of the body of said cap, said band being adapted to stretch in the application of the cap to the wearer's head and 60 have broad water-tight engagement with the head.

3. A bathing cap comprising a hollow body of flexible material having a head opening at the bottom defined by a marginal edge portion 70 adapted to fit around the head of the wearer, and a sealing flange of elastic material extending around the interior of said body and joined along its outer edge with said body in upwardly spaced relation to the edge of the marginal edge portion, 75

- said flange having a free inner edge portion which when the cap is applied to the head extends downwardly from the line of connection between the flange and body in laterally spaced 5 relation to the aforesaid marginal edge portion of the body of the cap so as to form with said marginal edge portion a water entrapping channel around the interior of the body of the cap, the inner edge portion of the flange being enlarged 10 to define a continuous circumferential bead on the edge thereof and being adapted to be stretched in the application of the cap to the wearer's head so that the beaded edge is caused to lie in snug water-tight engagement with the head, the inner edge portion of the flange being formed with 15 relation to that portion joined to the body of the cap so as to define a generally T-shaped cross-section, the cross-portion of the T being disposed substantially parallel to the adjacent wall of the cap and forming an annular sealing band extending entirely around the interior of the body of said cap, said band being adapted to stretch in the application of the cap to the wearer's head and have broad water-tight engagement 20 with the head, the bead being provided on the lower edge of the cross-portion.
5. A bathing cap comprising a hollow body of flexible material having a head opening at the bottom defined by a marginal edge portion adapted to fit around the head of the wearer, and a sealing flange of elastic material extending around the interior of said body and joined along its outer edge with said body in upwardly spaced relation to the edge of the marginal edge portion, said flange having a free inner edge portion 25 which when the cap is applied to the head extends downwardly from the line of connection between the flange and body in laterally spaced relation to the aforesaid marginal edge portion of the body of the cap so as to form with said 30 marginal edge portion a water entrapping channel around the interior of the body of the cap, the inner edge portion of the flange being enlarged to define a continuous circumferential bead on the edge thereof, which projects inwardly 35 relative to the flange, said inwardly projecting portion of the bead forming a sealing means for impressing engagement with the head, said bead also reinforcing said edge portion, said beaded edge portion being adapted to be stretched in 40 the application of the cap to the wearer's head so that the beaded edge is caused to lie in snug water-tight engagement with the head.
4. A bathing cap comprising a hollow body of flexible material having a head opening at the bottom defined by a marginal edge portion adapted to fit around the head of the wearer, and a sealing flange of elastic material extending around the interior of said body and joined along its outer edge with said body in upwardly spaced relation to the edge of the marginal edge portion, said flange having a free inner edge portion which when the cap is applied to the head extends downwardly from the line of connection between the flange and body in laterally spaced relation to the aforesaid marginal edge portion of the body of the cap so as to form with said marginal edge portion a water entrapping channel around the interior of the body of the cap, the inner edge portion of the flange being enlarged to define a continuous circumferential bead on the edge thereof, which projects inwardly relative to the flange, said inwardly projecting portion of the bead forming a sealing means for impressing engagement with the head, said bead also reinforcing said edge portion, said beaded edge portion being adapted to be stretched in the application of the cap to the wearer's head so that the beaded edge is caused to lie in snug water-tight engagement with the head.

J. CLAUDINE JOHNSON.
